UNITED STATES PATENT OFFICE.

JAMES M. WALSH, OF MILWAUKEE, WISCONSIN, ASSIGNOR TO JAMES M. WALSH CO., OF MILWAUKEE, WISCONSIN, A CORPORATION OF DELAWARE.

CROWN RING.

Application filed February 7, 1925. Serial No. 7,589.

This invention relates to improvements in crown rings used in harness construction.

Crown rings as now ordinarily made are in the form of a ring to which some of the 5 different strap portions forming the bridle are connected. The said construction does not present a finished appearance and the connected straps are not properly held in position and can swing out of alinement and 10 cause considerable wear on the straps.

It is one of the objects of the present invention to overcome the above objectionable features and provide a crown ring constructed to permit a better connection of the brow 15 strap in front, crown strap on top and cheek strap below, and having a rear edge ring portion for receiving a throat strap connector.

A further object of the invention is to 20 provide a crown ring formed to conveniently receive the different straps and having means for preventing the needle in sewing the straps to the ring from running off the edges of the straps.

25 A further object of the invention is to provide a crown ring having means for preventing dust and dirt from working into the spaces formed by the loops of the straps.

A further object of the invention is to 30 provide a crown ring which is of simple construction, is strong and durable and is well adapted for the purpose described.

With the above and other objects in view the invention consists of the improved crown 35 ring and its parts and combinations as set forth in the claims and all equivalents thereof.

In the accompanying drawing in which the same reference characters indicate the 40 same parts in all of the views:

Fig. 1 is a perspective view of the upper portion of a bridle provided with the improved crown ring;

Fig. 2 is a side view on a larger scale, of 45 the crown ring with some of the straps removed, and one of the straps partly broken away; and

Fig. 3 is a sectional detail view taken on line 3—3 of Fig. 2.

50 Referring to the drawing the numeral 5 indicates cheek bands or straps, 6 the crown band or strap, 7 the brow band or strap, and 8 one of the blinds. Said blinds are connected to the cheek straps in any manner desired. Each improved crown ring 9 is

preferably in the form of a casting and is provided with a central elongated slot or opening 10 through which extends the loop 5' of the cheek strap 5 and the loop 6' of the head strap 6. The said slot is formed 60 by an upper transverse bar portion 11, a lower transverse bar portion 12 and opposite side bar portions 13 and 14 which extend above and below the transverse bar portion to form stitch line supports 15 which are 65 tapered upwardly and downwardly to fit the tapering spaces 16 formed by the strap loops 5 and 6. The transverse bar portions 11 and 12 are provided with upwardly and downwardly extending tongues 11' and 12' 70 respectively, which also form stitch line supports. The forward edge portion of the crown ring is provided with an eye 17 of elongated form vertically, through which eye the looped portion 7' of the brow band 75 7 extends. The rear edge portion of the crown ring is also provided with an eye 18 and the opening of which is somewhat of egg formation with the larger diameter at the lower part to receive the connector hook 80 member 19 of the throat strap 20. Said connector carries a ring 21 through which the reins 22 extend.

The bars and eyes of the crown ring are 85 so formed and proportioned as to hold the cheek and head straps in alined position with relation to each other and the brow band is maintained in a position extending at approximately right angles to the cheek and head straps. The throat strap connector eye 18 is also formed to pivotally and 90 removably hold the throat strap in alined position with the eye while permitting movement of said throat strap.

In sewing the portions of the loops which 95 extend through the elongated slot of the crown ring the thickness of the metal between the portions of the leather causes the needle to run off the side of the strap in sewing and in order to overcome this 100 difficulty the crown ring is formed with the supporting extensions 15 and the medial supporting tongues 11' and 12'. These tongues and extensions are so positioned as to support the two portions of the strap forming 105 the loop and hold said portions in flat position for sewing the lines of stitching 23 between the extensions and the tongues as clearly indicated in Fig. 2. The extensions 15 also serve to fill up the spaces between 110

the portions of the strap forming the loop and prevent the entry of dust and dirt therein. Furthermore said extension, tongues and the lines of sewing also serve to hold 5 the straps and crown ring in alined positions.

From the foregoing description, it will be seen that the crown ring is of very simple construction and is well adapted for the purpose described.

10 What I claim as my invention is:

1. A crown ring consisting of a member having an elongated medial opening and eyed portions at the front and rear edges of the said member for connection with a 15 brow strap and a throat strap connector, the elongated opening being formed to receive cheek and head straps, the rear edge eye portion being of elongated form vertically and having a widened portion at its lower 20 end.

2. A crown ring consisting of a flat member provided with an elongated medial opening having its longest length extending horizontally for connection with head and cheek 25 straps, the front and rear edge portions of the member having eyes for connection with a brow strap and a throat strap connector, the rear edge eye portion being of elongated form vertically and having a widened portion 30 at its lower end.

3. A crown ring consisting of a flat member provided with an elongated medial opening having its longest length extending horizontally for connection with head and cheek 35 straps, the forward and rearward edge portions of the member having eyes, the forward eye being of elongated form with the greatest length extending vertically for connection with a brow strap, and the rearward eye being of rounded elongated form with a widened portion at its lower end, said rearward eye being adapted to removably receive a throat strap connector.

4. A crown ring consisting of a member provided with an elongated medial opening having its longest length extending hori-

zontally for connection with the head and cheek straps, said member also having extensions for supporting edge portions of the straps while being sewed, the forward and 50 rearward edge portions of the member having eyes, the forward eye being of elongated form with the greatest length extending vertically for connection with a brow strap, and the rearward eye being of rounded 55 elongated form for removably receiving a throat strap connector.

5. A crown ring consisting of a member provided with an elongated medial opening having its longest length extending horizontally 60 for connection with head and cheek straps, said member also having upwardly and downwardly projecting extensions for supporting edge portions of the straps while being sewed to the member, the forward and 65 rearward edge portions of the member having eyes, the forward eye being of elongated form with the greatest length extending vertically for connection with a brow strap, and the rearward eye being approximately 70 of egg shape with the larger diameter below for removably receiving a throat strap connector.

6. A crown ring consisting of a member provided with an elongated medial opening 75 having its longest length extending horizontally for upward connection with a head strap and downward connection with a cheek strap, said member also having upper and lower edge extensions and medial tongues 80 for supporting edge and medial portions of the straps while being sewed to the member, the forward and rearward edge portions of the member having eyes, the forward eye being of elongated form with the greatest 85 length extending vertically for connection with a brow strap, and the rearward eye being approximately of egg shape with the larger diameter below for removably receiving a throat strap connector.

In testimony whereof, I affix my signature.
JAMES M. WALSH.
